LAMP SHADE

Ben J. Seger, 5 Mead Lane, Roslyn, N.Y. 11576

Filed Aug. 26, 1968, Ser. No. 13,265

Term of patent 3½ years

Int. Cl. D26—06

U.S. Cl. D48—16

FIG. 1

FIG. 1 is a side elevational view of the lamp shade showing my design.

FIG. 2 is a top plan view thereof.

In FIGURE 1, the central facing panel constitutes a repeat unit being one of six repeat units surrounding the circular skirt of the shade.

I claim:

The ornamental design for a lamp shade, as shown and described.
